UNITED STATES PATENT OFFICE.

MILTON V. WASH, OF BEAVER FALLS, PENNSYLVANIA, ASSIGNOR TO BEAVER FALLS ART TILE COMPANY, OF BEAVER FALLS, PENNSYLVANIA, A CORPORATION OF PENNSYLVANIA.

TILE PRESS.

Application filed April 4, 1925. Serial No. 20,701.

To all whom it may concern:

Be it known that I, MILTON V. WASH, a citizen of the United States, and a resident of Beaver Falls, in the county of Beaver and 5 State of Pennsylvania, have invented a new and useful Improvement in Tile Presses, of which the following is a specification.

The object of this invention is to provide a tile press of the general character of that 10 disclosed in U. S. Patent No. 1,515,918 to Yingling with a lower die which is rigidly supported during pressing operations, and with simple and effective mechanism for effecting the movement of the lower die upwardly with the upper die at the completion 15 of a pressing operation, and downwardly thereafter independently of the upper die.

The invention is illustrated in the accompanying drawings of which Fig. 1 is a vertical sectional view of a tile press, the plane of view being indicated by the line I—I, Fig. 2; Fig. 2 a vertical sectional view at right angles to Fig. 1, the plane of view being indicated by the line II—II, Fig. 1; Fig. 3 a plan view of pressure controlling operating mechanism, the plane of view being generally indicated by the line III—III, Fig. 2, the valve casing shown in this view being indicated in section; Fig. 4 a sectional view taken on the line IV—IV, Fig. 3; and Fig. 5 an elevation taken on the plane indicated by the line V—V, Fig. 3.

The machine comprises a frame 1 in which 35 there is mounted for vertical reciprocation a plunger 2 provided on its lower end with an upper die 3. The plunger may be vertically reciprocated by means of a pair of toggle links 4 and 5, pivoted to each other 40 at 6, the upper end of link 4 being pivotally suspended from a support 7, and the lower end of link 5 being pivotally attached at 8 to plunger head 2. The pivot point 6 of the toggle levers may be moved horizontally to 45 raise and lower plunger 2 by means of an arm 9, the outer end of which may be engaged by a cam borne by a rotary driven shaft 10. The parts of the press thus far explained are shown in dotted lines because 50 they are fully disclosed in said patent to Yingling, to which reference may be made for a more detailed explanation of their construction and operation.

For the purpose of the present invention it

is sufficient to state that in the operation of this particular form of tile press the plunger is alternately raised and lowered by the lateral movement of arm 9; that, while the plunger is raised, dust for forming one or more tiles is placed in the lower die; that 60 the plunger is then moved downwardly to form a tile; and that as the plunger rises after a tile-pressing operation the lower die is caused to rise with it so as to properly hold the tile in its pressed form until removed from the side walls of the die. While for the purpose of illustrating the invention it is shown in connection with a tile press similar to that disclosed in said Yingling patent, it will be understood that the vertical reciprocation of the plunger may be otherwise effected than as shown in said patent, and as generally explained above.

Having reference to Figs. 1 and 2, a lower die 12 is mounted on an anvil 13 which is 75 movable vertically with the upper die to raise pressed tiles, indicated at 14, above vertical walls 15 and 16 which form their sides and ends. When in its lowermost position, anvil 13 is firmly and unyieldingly 80 supported by the top of a base block 17 which is provided with cylindrical openings 18 and 19 for receiving pressure fluid. Arranged in cylinders 18 there are pistons 20 attached to anvil 13 by bolts 21, the arrangement being such that when fluid pressure enters the lower ends of cylinders 18 pistons 20 are moved upwardly to raise anvil 13. In 85 cylinders 19 there are pistons 22 attached to anvil 13 by bolts 23, the arrangement being 90 such that when fluid pressure enters the upper ends of cylinders 19 it will act upon the tops of pistons 22 to move the anvil downwardly until it becomes seated upon the upper end of base block 17. 95

For supplying pressure fluid alternately to cylinders 18 and 19, and for alternately controlling exhaust from these cylinders, there is provided a valve preferably having a substantially cylindrical casing 25 (Fig. 100 3) within which there is a longitudinally movable valve element having two heads 26 and 27 rigidly connected to each other by a stem 28, and forming between them and with casing 25 an air-tight annular chamber 29 to which pressure fluid, preferably compressed air, is supplied through a pipe 105 30. The movable valve element is attached

to a rod 31 adapted to be reciprocated in the manner presently to be explained.

The ends of casing 25 are provided with exhaust ports 32 and 33, and the side wall of the casing is provided with ports 34 and 35 which communicate, respectively, with chambers 36 and 37 formed on the side of base block 17. As seen in Fig. 5, these chambers are of general triangular shape, being separated from each other by an inclined partition 39, the outlets of ports 34 and 35 being there indicated in dotted lines at the outer ends of chambers 36 and 37, respectively. Extending from the lower end of chamber 37, there are passageways 40 which lead through base block 17 to the lower ends of cylinders 18. In a similar manner, extending from the upper end of chamber 36 there are passageways 41 leading to the upper ends of cylinders 19. Through these ports, chambers and passageways pressure fluid is alternately supplied to cylinders 18 and 19, and exhaust is alternately carried from the cylinders, depending upon the position of the valve element as will presently be explained.

For moving the valve element in casing 25 to effect the upward and downward movements of anvil 13, a cam 45 is attached to a rotatable gear 46, which in turn is secured to driving shaft 10, and connections extend from this cam to rod 31 attached to the valve element. These connections include a rock shaft 47 to which there is attached an arm 48 pivotally connected by a short link 49 to the outer end of rod 31. A second arm 50 is attached at its lower end to rock shaft 47 and is connected at its upper end by a link 60 to the outer end of an arm 51, attached to a vertically disposed rock shaft 52. At the upper end of shaft 52 there is a horizontally disposed arm 53, to which there is pivotally attached an extension arm 54 having a roller 55 at its outer end adapted to engage cam 45. Roller 55 is yieldingly urged upwardly into cam-engaging position by a spring 56 which acts between arm 54 and the lower end of a bar 57 which is attached to arm 53. Arm 54 is connected by a link 58 to a lever arm 59 for disconnecting the charging and agitating apparatus from each other as explained in said Yingling patent, it being understood that when these two mechanisms are disconnected from each other it is desirable to stop the vertical reciprocation of anvil 13. Accordingly, when operating lever 59 is turned downwardly, link 58 pulls arm 54 downwardly against the resistance of spring 56 so that roller 55 lies below the path of cam 45.

The valve operating connections thus described are for moving the valve element from the position in which it is indicated in Fig. 3 to its alternate position, which is at the right end of casing 25 as viewed in

Fig. 3. For moving the valve element in the opposite direction, a spring 71 is arranged in a housing 72 attached to the left end of casing 25, such spring bearing at its opposite ends upon head 26 and a nut surrounding rod 31 and engaging the outer end of this housing. A light weight buffer spring 61 is arranged in a housing 62 at the opposite end of the casing for preventing impact of the movable valve element upon that end of the casing.

Through the connections extending from valve rod 31 to cam-engaging arm 54, spring 71 normally acts to yieldingly urge cam roller 55 into the path of cam 45. For manually controlling the position of the valve element when occasion arises for doing so, rock shaft 47 has attached to it a horizontally disposed arm 65, to the outer end of which there is pivotally connected the lower end of a vertical link 66, the upper end of which is pivotally attached to a hand operated lever 67 pivoted to frame 1 at 68.

In the operation of the machine, assuming the parts to be in the positions indicated in the drawings, the rotation of gear 46 brings cam 45 out of engagement with roller 55, which permits spring 71 to move the valve element to the right hand end of the casing as viewed in Fig. 3. The train of connections for thus moving valve rod 31 has been fully explained, and accordingly need not be here repeated. When the valve element is thus in the opposite position from that shown in the drawings, the upper ends of cylinders 19 are open to exhaust through passageways 41, chamber 36, ports 34 and exhaust passageway 32. Pressure fluid is then supplied to the lower ends of chambers 18 through pipe 30, chamber 29 between heads 26 and 27 of the valve element, port 35, chamber 37, and passageways 40. The pressure fluid thus supplied to the lower ends of cylinders 18 below pistons 20 causes anvil 13 to rise with the upward movement of plunger head 2 and upper die 3. This movement is continued until the pressed tiles are above the upper edges of side plates 15 and 16, and die 12 is maintained in its upper position until the tiles are removed from it. At this time the end of cam 45 engages roller 55, and moves the valve element to the left against the resistance of spring 71, in which position pressure fluid is supplied to the upper ends of cylinders 19 to move the anvil downwardly, and the lower ends of cylinders 18 are open to exhaust. The flow of pressure fluid and of exhaust to cause this downward movement of the anvil will be readily understood from the foregoing explanation of the opposite flow of pressure fluid and exhaust.

According to the provisions of the patent statutes, I have explained the principle and operation of my invention, and have shown

and described what I now consider to represent its best embodiment. However, I desire to have it understood that, within the scope of the appended claims, the invention 5 may be practiced by other forms of construction than those specifically illustrated and described.

I claim as my invention:

1. In a tile press, the combination of a 10 reciprocable plunger provided with an upper die, a base block provided with two pressure cylinders, an anvil mounted for vertical movement in said block and provided with a lower die, raising and lowering 15 pistons attached to said anvil and arranged in said pressure cylinders, a valve comprising a casing communicating with said cylinders and an element movable to alternate positions for alternately controlling 20 flow of pressure fluid to an exhaust from said cylinders, and means coordinated with the reciprocation of said plunger for moving said valve element.
2. In a tile press, the combination of a 25 reciprocable plunger provided with an upper die, a base block provided with two pressure cylinders, an anvil mounted for vertical movement in said block and provided with a lower die, raising and lowering pistons attached to said anvil and arranged in said 30 pressure cylinders, a valve comprising a casing communicating with said cylinders and an element movable to alternate 35 positions for alternately controlling flow of pressure fluid to and exhaust from said cylinders, a rotary cam coordinated with the reciprocation of said plunger, and connections extending from said cam to said valve element for moving the latter.
3. In a tile press, the combination of a 40 reciprocable plunger provided with an upper die, a base block provided with two pressure cylinders, an anvil mounted for vertical movement in said block and provided with a lower die, raising and lowering pistons attached to said anvil and arranged in said 45 pressure cylinders, a valve comprising a casing communicating with said cylinders and an element movable to alternate positions 50 for alternately controlling flow of pressure fluid to and exhaust from said cylinders, a rotary cam coordinated with the reciprocation of said plunger, connections extending from said cam to said valve element for moving the latter to one of its alternate 55 positions, and a spring acting upon said valve element for moving it to the other of its alternate positions.
4. In a tile press, the combination of a 60 reciprocable plunger provided with an upper die, a base block provided with two pressure cylinders, an anvil mounted for vertical movement in said block and provided with a lower die, raising and lowering pistons 65 attached to said anvil and arranged in said

pressure cylinders, a valve comprising a casing communicating with said cylinders and an element movable to alternate positions for alternately controlling flow of pressure fluid to and exhaust from said cylinders, a rotary cam coordinated with the reciprocation of said plunger, an arm adapted to be engaged by said cam, connections between said arm and said valve element for moving the latter to one of its alternate 70 positions, and a spring for moving said valve element to the other of its alternate positions and for maintaining said arm normally in the path of said cam.

5. In a tile press, the combination of a 75 reciprocable plunger provided with an upper die, a base block provided with two pairs of pressure cylinders, an anvil mounted for vertical movement in said block and provided with a lower die, a pair of raising 80 pistons arranged in one of said pairs of pressure cylinders and attached to said anvil, a pair of lowering pistons arranged in the other of said pairs of pressure cylinders and attached to said anvil, a valve comprising a 85 cylindrical casing communicating at one of its ends with one of said pairs of pressure cylinders and at its other end with the other of said pairs of pressure cylinders, a valve element mounted for reciprocation in said casing for alternately controlling flow of pressure fluid to and exhaust from said pairs of cylinders, and means coordinated with the reciprocation of said plunger for moving said valve element.

6. In a tile press, the combination of a 90 reciprocable plunger provided with an upper die, a base block provided with two pairs of pressure cylinders, an anvil mounted for vertical movement in said block and provided with a lower die, a pair of raising 95 pistons arranged in one of said pairs of pressure cylinders and attached to said anvil, a pair of lowering pistons arranged in the other of said pairs of pressure cylinders and attached to said anvil, a valve comprising a 100 cylindrical casing communicating at one of its ends with one of said pairs of pressure cylinders and at its other end with the other of said pairs of pressure cylinders, a valve element mounted for reciprocation in said casing for alternately controlling flow of pressure fluid to and exhaust from said pairs of cylinders, and means coordinated with the reciprocation of said plunger for moving said valve element.

7. In a tile press, the combination of a 105 reciprocable plunger provided with an upper die, a base block provided with two pairs of pressure cylinders, an anvil mounted for vertical movement in said block and provided with a lower die, a pair of raising 110 pistons arranged in one of said pairs of pressure cylinders and attached to said anvil, a valve comprising a 115 cylindrical casing communicating at one of its ends with one of said pairs of pressure cylinders and at its other end with the other of said pairs of pressure cylinders, a valve element mounted for reciprocation in said casing for alternately controlling flow of pressure fluid to and exhaust from said pairs of cylinders, a rotary cam coordinated with the reciprocation of said plunger, and connections extending from said cam to said valve element for moving the latter.

8. In a tile press, the combination of a 120 reciprocable plunger provided with an upper die, a base block provided with two pairs of pressure cylinders, an anvil mounted for vertical movement in said block and provided with a lower die, a pair of raising 125 pistons arranged in one of said pairs of pressure cylinders and attached to said anvil,

a pair of lowering pistons arranged in the other of said pairs of pressure cylinders and attached to said anvil, a valve comprising a cylindrical casing communicating at one of its ends with one of said pairs of pressure cylinders and at its other end with the other of said pairs of pressure cylinders, a valve element mounted for reciprocation in said casing for alternately controlling flow of pressure fluid to and exhaust from said pairs of cylinders, a rotary cam coordinated

with the reciprocation of said plunger, a movable arm lying in the path of said cam, connections between said arm and said valve element for moving the latter to one of its alternate positions, and a spring for moving said valve element to the other of its alternate positions and for maintaining said arm normally in the path of said cam.

In testimony whereof, I sign my name.

MILTON V. WASH.
